DOOR HANDLE

Norman R. Adler, Fitchburg, Mass., assignor to Independent Lock Company, Fitchburg, Mass., a corporation of Massachusetts

Filed June 29, 1965, Ser. No. 85,948

Term of patent 14 years

(Cl. D50—5)

FIG. 1

FIG. 2

FIG. 3

FIG. 4

The dominant features reside in full line portions.

I claim:

The ornamental design for a door handle, substantially as shown and described.
